(57) CLAIM

The ornamental design for a make-up brush chart, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top plan view of a make-up brush chart showing a first embodiment my new design;

FIG. 2 is a top plan view of a second embodiment thereof;

FIG. 3 is a top plan view of a third embodiment thereof; and, FIG. 4 is a top plan view of a fourth embodiment thereof.

The broken line showing of the card is for the purpose of illustrating portions of the make-up brush chart and forms no part of the claimed design.

1 Claim, 4 Drawing Sheets
(2 of 4 Drawing Sheet(s) Filed in Color)

FIG. 1

Fairweather Faces
(Professional, Travel Size, Color-Coded, Multi-Functional)

Make-up Brushes

Match colors of Make-up Brush to Box on Face Chart, and SNAP! Apply year Make-up like the Pros...

These 'space saver' multi-functional brushes are not only cute, but a necessary tool for Professional Make-up Artists and Everyday Clientele. If the hairs are cut in layers to create an effortless, flawless make up application.

Camouflage-Use to apply concealer / spot treatment or overall foundation

Bonus: Great for applying cream eyeshadow

Classic Blush-Multi functional

Concealer/Blush/Bronzer-Simply tissue off in between each use

Bonus: Overall blending tool

Classic Deluxe Fluff-Perfect for quick, full eyeshadow applications

Bonus: Can blend cream eyeshadows

Mini Detail-Deluxe, Standard eyeshadow/liner brush-Use to define or soften

Bonus: Use dry or wet

Brush Care Wash by holding handle downward (wet hairs only in running luke warm water); Lather with baby shampoo; Rinse(hairs only) under cool running water; Gently squeeze out excess water (downward position, away from brush handle); Dry on clean surface-open window sill is best.

FIG. 4
